13 Claims. (Cl. 62—119.5)

1

The present invention relates to absorption refrigerating apparatus of the type in which a heat-operated pump maintains liquid circulation through the boiler of the apparatus and in which the heat supply to the pump and the boiler takes place through the medium of a flue or like heat-transferring member. The object of the invention is to make possible a more suitable arrangement of certain parts of the refrigerating apparatus, particularly its liquid heat exchanger and, in certain cases, at the same time improve the efficiency of the boiler by an improved rectification of the boiler vapours.

It has previously been proposed to give the boiler the shape of a jacket placed round a flue and the liquid pump the shape of a tube coil wound round the lower part of the flue located between the lower edge of the jacket and that of the flue. The poor solution is taken out from the boiler through a tube connected to its lowest part, whereas the supply of rich solution to the pump takes place through a conduit connected to the pump coil arranged below the boiler. The lower part of the flue is thus always cooled by the solution passing through the pump and the liquid content of the higher located boiler jacket.

It has previously been proposed to build into the boiler insulation besides the boiler and its pump also the liquid heat exchanger of the apparatus in order to reduce in this manner the losses through radiation. It has, however, proved extremely difficult to realize this proposal in actual practice, because the liquid heat exchanger must be arranged in such a manner that the gas bubbles possibly produced therein can be evacuated freely and with certainty. The simplest solution of this problem has proved to consist in winding the exchanger in a coil e. g. concentric with the flue and located immediately below the pump. Especially in the case of gas and oil operation this arrangement of the exchanger is, however, inconvenient owing to the difficulty of disposing the heat source. According to the present invention all these difficulties are, however, eliminated, this being effected substantially by extending the boiler downwardly from the liquid pump and arranging the extended part in heat-conducting contact with the likewise downwardly extended flue. This makes it possible to extend the liquid heat exchanger in the manner indicated above and to place the heat source on a level with the lower edge of the exchanger or on a lower level without any overheating of the downwardly extended flue with its attendant ruining of the flue material and high increase of the losses through

radiation owing to the overheating. The boiler being extended downward to a level below the pump, a corresponding shortening of the part of the boiler located above the pump may be effected in many cases, since, in spite of such a shortening, the heat-absorbing capacity of the boiler will be sufficient. If desired, the upper part of the boiler may be thermally separated from the flue and formed into a rectification column without outer heat supply.

The invention will in the following be more fully described with reference to the embodiments shown diagrammatically in the accompanying drawings from which the characteristic features of the invention will be seen and in which

Fig. 1 shows diagrammatically an absorption refrigerating apparatus operating with an inert gas; Figs. 2, 3 and 4 show a number of modified embodiments of the boiler according to Fig. 1; and Fig. 5 is a cross-sectional view of the boiler on line 5—5 in Fig. 2.

In Fig. 1, 10 designates a tube operating as a flue, to which another tube 11 is welded along a common generatrix. Below, the tube 11 is closed, whereas, above, it passes into a conduit 28 leading to the condenser 18 of the apparatus. The tube 11 serves as a boiler, and the vapours expelled are led through the conduit 28 to the condenser. The poor solution flows through a conduit 30, the outer jacket of the liquid heat exchanger 13 and the conduit 14 to the absorber 15 of the apparatus. The liquid circulation pump of the apparatus is designated by reference numeral 12 and is formed of a narrow tube which, below, is a continuation of the inner tube of the heat exchanger 13 and, above, runs into the boiler tube 11 into which the rich solution is thus pumped. This solution is supplied through 40 the inner tube of the heat exchanger 13 from the absorber vessel 16 of the apparatus. As already stated, the refrigerating apparatus shown in Fig. 1 works with the help of an inert gas, which, in a manner known per se, circulates 45 through the evaporator of the apparatus, not shown, as well as its gas heat exchanger designated by reference numeral 20, a conduit 21, the absorber vessel 16, the absorber 15, the exchanger 20 and finally the evaporator. The liquid refrigerant is supplied to the evaporator from the condenser 18 through a conduit 19 provided with a U-seal. Finally, a pressure vessel 25 of a kind known per se is, in the embodiment shown, connected by means of conduits 27 and 26 to the circulation system of the gas. Both the condenser

18 and absorber 15 may be air-cooled and, if desired, provided with cooling fins.

As appears from Fig. 1, the poor solution is carried off from the boiler tube 11 from a part of same located substantially higher than the bottom of the boiler, a pocket without a bottom outlet being thus formed. This liquid pocket is, however, like the remainder of the boiler, in heat-conducting connection with the flue 10 and receives from the latter considerable quantities of heat. In the embodiment shown, the heat source is, in fact, assumed to be located at the lower mouth of the flue 10, the walls of which are thus directly heated. The pump 12 is, along a certain length, welded to the tube 10, on a level with or somewhat above the level of the outflow of the poor solution from the boiler. The connecting conduits from the exchanger to the boiler or the pump, respectively, will thus be very simple and short, particularly if the liquid heat exchanger is arranged in the shape of a tube coil wound around the boiler, inclusive of the pump and flue, said coil, together with the boiler, being provided with a hood or the like of heat-insulating material, not shown.

It is generally desirable to effect a regulated circulation of the solution also in the part of the boiler located below the pump in order to prevent said solution being too vigorously boiled out, as otherwise its refrigerant concentration would be too low. In order to bring about such a circulation it is possible as shown diagrammatically in Fig. 2, to insert a partition 31 into the boiler tube 11, said partition terminating below somewhat above the bottom of the boiler and, above, somewhat above the entry of the pump tube into the boiler tube 11. Fig. 5 shows diagrammatically a cross section along the line 5-5 of the boiler tube 11 in Fig. 2. The partition 31 is suitably welded along the inner surface of the tube by spot welding which may be effected electrically with two electrodes disposed diametrically on the outside of the tube. The partition is so disposed that the relatively rich solution raised by the pump is supplied to the tube half located nearest to the flue where the boiling of the solution continues, its concentration gradually decreasing. By the raised liquid the liquid column in said boiler half is continually pressed downward, passing at the bottom to the boiler half located on the left in the upward direction and being supplied to the absorber through the conduit 30 and the heat exchanger 13. In the part of the left half of the boiler located above the pipe 30 for the poor solution a boiling-out also takes place, partly owing to direct heat transfer through the partition 31 and by way of the jacket wall of the tube from the flue, partly generally also through the rising vapour. The solution in the upper part of the left boiler half is, in fact, generally richer than any other solution in the boiler, this being due to the fact that the condensate precipitated in the vapour tube 28 and a rectifier arranged; if desired, behind said tube flows down along the bottom of the vapour tube into the left boiler half. It is thus evident that the partition not only effects a regulated flow through the pocket of the boiler but also a certain rectification of the boiler vapours, the vapours expelled from the lower parts of the boiler and relatively rich in absorption medium being forced to pass through liquid layers having a higher concentration.

Instead of a simple partition it is possible, as shown diagrammatically in Fig. 3, to arrange in-

side the boiler tube 11 a suitably concentrically located tube 32 which, below, terminates somewhat above the bottom of the boiler and into the upper part of which runs the pump tube 12. In a manner wholly analogous to what has been described in connection with Fig. 2 a regulated flow of boiler solution is obtained in this case from the inner tube downwards and along the boiler tube 11 up to the pipe 30 for the poor solution.

Fig. 4 shows a further embodiment of the boiler according to the invention. In this boiler the partition has been replaced by an insert 33 comprising a band the width of which corresponds approximately to the inner diameter of the tube and in which tongues 34 have been punched and alternately bent at right angles to both sides of the band. Inserts of this kind previously used in rectifiers possess, as is well known, the quality of facilitating rectification by, on the one hand, preventing the intermixture of different liquid layers and, on the other hand, by effecting an intimate contact between the vapour and the liquid. The solution will thus flow in the vertical direction only to a very limited extent and for this reason it is not generally suitable to let an insert of this type extend downwards into the pocket of the boiler, as this would make the solution in the pocket extremely poor and considerably increase the temperature and the pressure. In the device according to Fig. 4 there does not, however even if the insert terminates above the tube 30, ensue any regulated flow in the pocket, but it has been proved that the movement of boiler solution is enough for preventing an increase of temperature disturbing the operation.

The invention may be varied in several ways, without departing from the spirit of the invention, and is not thus limited to the examples shown diagrammatically. Therefore, without limiting myself in this respect, the invention is defined by the appended claims:

I claim:

1. In an absorption type refrigerating system, an upright heating flue, and a circuit for absorption liquid including a generator vessel having a wall in heat transfer relation with said flue, an absorber, and a heat operated vapor lift conduit separate from and outside of said generator and having a heat receiving and vapor forming part which is in heat transfer relation with said flue and arranged in said circuit to receive liquid from said absorber and deliver liquid to said generator, the heat transfer relation between said generator and flue being at least in part at an elevation below that of said part of said vapor lift conduit.
2. In an absorption type refrigerating system, an upright heating flue, and a circuit for absorption liquid including a generator vessel having a wall in heat transfer relation with said flue, an absorber, a heat operated vapor lift conduit separate from and outside of said generator and having a heat receiving and vapor forming part which is in heat transfer relation with said flue and arranged in said circuit to receive liquid from said absorber and deliver liquid to said generator, the heat transfer relation between said generator and flue being at least in part at an elevation below that of said part of said vapor lift conduit, and a conduit for conducting to said absorber liquid from said generator, said last conduit communicating with said generator so that the lower part of said generator forms a liquid pocket below the conduit.

3. A system as set forth in claim 2 in which said generator is provided internally with baffle structure for directing movement of fluid therein.

4. A system as set forth in claim 2 in which said generator is provided internally with wall structure for directing flow of liquid therein in a path running through said pocket.

5. A system as set forth in claim 1 in which said generator is provided internally with baffle structure to direct movement of fluid therein.

6. A system as set forth in claim 1 in which said generator is provided internally with wall structure arranged to cause flow of liquid therein downward in one part of the generator and upward in another part of the generator.

7. A system as set forth in claim 2 in which said generator is a tube secured in thermal contact to said flue and closed at its lower end.

8. A system as set forth in claim 2 in which said circuit for absorption liquid also includes a heat exchanger in the form of a tube coil located around the liquid pocket part of said generator.

9. A system as set forth in claim 2 in which said generator is provided internally with baffle structure in the upper part thereof to form a rectifying column.

10. A system as set forth in claim 2 in which said generator is a tube closed at its lower end,

and said generator is provided internally with a tubular partition wall dividing the generator into chambers communicating at their upper and lower ends.

11. A system as set forth in claim 1 in which said generator is provided internally with a partition dividing the generator into chambers communicating at their upper and lower ends.

12. An absorption type refrigeration system employing inert gas and having a generator with an outlet a substantial distance above the bottom thereof, said outlet forming a pocket in the generator therebelow holding a body of liquid out of circulation in the system, and a heating flue arranged in heat conductive relation with one side of the generator vessel to cause local circulation of the pocketed body of liquid.

13. An absorption type refrigeration system employing inert gas and having a vessel with an outlet a substantial distance above the bottom thereof, said outlet forming a pocket in the vessel therebelow holding a body of liquid out of circulation in the system, and a heating conduit arranged in heat conductive relation with one side of the vessel to cause local circulation of the pocketed body of liquid.
